(57) **CLAIM**

The ornamental design for a massage device, as shown and described.

DESCRIPTION

FIG. 1 is a perspective view of a massage device showing my new design;

FIG. 2 is a front view thereof; the rear view being the same thereof;

FIG. 3 is a left side view thereof; the right side view being the same thereof;

FIG. 4 is a top view thereof; and,

FIG. 5 is a bottom view thereof.

Any shading and cross-hatching are not features of the design but are utilized to illustrate the surface contours of the massage device design in the drawings.

1 Claim, 5 Drawing Sheets
